A. L. HALLIDAY CARPET

No. 14,292

September 18, 1883.

UNITED STATES PATENT OFFICE.

ARTHUR L. HALLIDAY, OF YONKERS, NEW YORK, ASSIGNOR TO THE
BIGELOW CARPET COMPANY, OF CLINTON, MASSACHUSETTS.

DESIGN FOR A CARPET.

SPECIFICATION forming part of Design No. 14,292, dated September 18, 1883.

Application filed August 3, 1883. Term of patent 3½ years.

To all whom it may concern:

Be it known that I, ARTHUR L. HALLIDAY, of Yonkers, in the county of Westchester and State of New York, have invented and produced a new and original Design for a Carpet, of which the following is a full description, in connection with the accompanying photograph, which represents a face view of my new design for a carpet.

10 This invention relates to the new configuration of the figures that ornament a carpet or analogous fabric.

15 In the accompanying photograph, letter A represents the central group of flowers, from which sprays and leaves extend outward in all directions, and which group is placed on a mottled background. This group A is placed between bouquets B and C, which flank it di-

agonally, one half of the bouquet B being shown at the right-hand side above the group 20 A, and the other half at the left-hand side below the group A, while one half of the bouquet C is shown on the left-hand side of the photograph above the group A, and the other at the right-hand side below said group A. 25 Directly above and below the group A are floral groups D, as shown.

I claim—

The design for a carpet, the same consisting of the figures A, B, C, and D, substantially 30 as shown.

ARTHUR L. HALLIDAY.
